GEORGE C. LEVY.
INVENTOR

By *Frank Harvey*
Attorney.

UNITED STATES PATENT OFFICE.

GEORGE C. LEVY, OF PITTSBURGH, PENNSYLVANIA.

CUFF.

1,187,348.

Specification of Letters Patent. Patented June 13, 1916.

Application filed July 24, 1915. Serial No. 41,770.

To all whom it may concern:

Be it known that I, GEORGE C. LEVY, a citizen of the United States of America, residing at Pittsburgh, in the county of Allegheny and State of Pennsylvania, have invented 5 certain new and useful Improvements in Cuffs, of which the following is a specification.

The present invention appertains to an improved form of cuff for men's shirts, and relates particularly to the type of cuff known as "soft" and reversible cuffs.

In all patterns of reversible cuffs with which I am familiar, when the cuff end is 10 turned inside the cuff, the extreme edge of the cuff presents an abrupt and loose obstruction to the free passage of the hand through the cuff, and when the hand so encounters this turned in edge, the cuff is 15 disarranged or rumpled, and oftentimes marred. These objectionable features and annoyances are eliminated by the utilization of a shield or flap that I employ to fit over the free end of the cuff when it is turned inside or reversed, and this shield confines the 20 edge of the cuff so that it is out of the way and permits the free passage of the hand through the cuff when the wearer is putting on the shirt.

30 The invention consists in the novel combination and arrangement of this shield or flap with the cuff, as will be more fully pointed out in the accompanying specification and claims.

35 In the drawings herewith I have illustrated one complete example, and a slight modification thereof, of the physical embodiment of my invention, made according to the best modes I have so far devised for the 40 practical application of the principles of my invention.

Figure 1 is a plan view of a cuff made according to my invention, showing the inside of the sleeve, with a corner of the flap and a 45 corner of the cuff turned back for convenience of illustration. Fig. 2 is a similar view with the cuff extended as in the act or being reversed, showing the shield or flap flat on the cuff. Fig. 3 is a perspective view of a 50 portion of the cuff, looking at the inside, showing the edge and the arrangement of the folded cuff and flap. Fig. 4 is a view similar to Fig. 3, but here the cuff is reversed. Fig. 5 is an outside perspective view 55 showing the cuff with its end turned inside under the shield. Fig. 6 shows a modified

form of the invention wherein the shield has its end edges sewed to the cuff, to form a pocket into which the cuff end is tucked.

In the preferred embodiment of my invention as illustrated in the drawings, the cuff 1 is attached to the sleeve portion 2 in usual manner, and is foldable on the line 3 3 in Fig. 2, the outer part 4 of the cuff being adapted to fold either outside the cuff or inside the sleeve as usual in reversible cuffs. The cuff is provided with the usual cuff-button holes 5, (four in number, one pair for the fixed portion 1 and the other pair for the foldable end portion 4.

The shield for the cuff end is a piece of fabric 6 preferably of the same material as the cuff, and in some instances the shield may be a portion of the cuff and sewed to the sleeve end so that it will overlap. In 75 the drawings however, the flap 6 is a separate piece of material, sewed to the inside of the sleeve at the base or top of the cuff, and the flap 6 is free at its ends and hangs loose inside the cuff. A pair of cuff-button 80 holes 7 7 are worked in the shield, one at each end, and these holes register with the button holes in the cuff portions, so that the shank of the cuff button passes through two sets of three holes in the cuff. At the under 85 side of the flap 6 and spaced equally from the center thereof are a pair of sockets as 8, 8 and these sockets are adapted to receive the correspondingly arranged balls 9 9 on the outer side of the end portion or foldable 90 portion 4 of the cuff. This ball and socket fastening, or glove fastener arrangement is effective in holding the cuff when it is reversed and the foldable end turned inside under the shield or flap, as clearly seen in 95 Fig. 1. When the edge of the cuff has become soiled it is turned in as in Fig. 1 and the foldable end is tucked under the shield and held there by the fastenings 8—9, and in addition, the cuff buttons which are 100 passed through the two sets of three holes each in the cuffs, hold the flap or shield securely in place.

When the cuff is being worn with the foldable end 4 outside, it will be noted that the 105 balls 9 of the glove fastening device are invisible as they are secured at what is now the inner side of the portion 4. The flap or shield is inoperative when the cuff is turned out, except that the button shanks are passed 110 through the holes 7 in addition to holes 5, but the flap, because of its cut away portion

10, forms no obstruction to the free passage through the cuff, of the hand or wrist.

When the cuff is to be reversed, after the buttons have been removed, the portion 4 is 5 folded under, and its end tucked up under the shield or flap and the ball and socket fasteners are snapped together, and when the cuff button has been secured in place the cuff is now ready for a second wearing.

10 The used end of the cuff is securely and effectively held under the shield, and the snug and close fit of the shield prevents any obstruction to the free passage through the cuff of the hand.

15 In Fig. 6 the shield as 11 is sewed at its end edges to the cuff in order to form a pocket for the cuff end 4^a and the cuff portion 4^a may be beveled at 12 in order to facilitate the entrance of the cuff end into the 20 pocket.

In Fig. 5 it will be noted that the edge of the cuff, from point *a* to point *b*, and thence around the cuff, is free, the line of stitches *c* which secures the cuff to the sleeve being 25 inset from the edge of the cuff for this purpose in order to give the cuff, when this side is exposed, the appearance of the ordinary soft cuff.

From the above description taken in connection with my drawings it is evident that 30 I have provided an improved cuff which will obviate the objectionable features enumer-

ated hereinbefore and prove a highly desirable feature in the modern soft reversible cuffs.

35

It will be evident that numerous changes and alterations may be made within the scope of my invention without departing from the spirit of my appended claims, and it should be understood that I contemplate 40 making alterations and changes as are desired or required to perfect the cuff according to several plans.

What I claim is:—

1. The combination with a sleeve and a 45 foldable cuff, of a shield fastened to the inside of the cuff and adapted to overlap its extreme edge when said edge is turned inside the cuff and means for fastening the foldable cuff to the shield, said cuff having 50 a seam of stitches near its edge forming a plait where it is attached to the sleeve to give the appearance of a folded ply to the cuff.

2. The combination with a sleeve and a 55 foldable cuff having two sets of button holes, of a flap having a cutaway portion forming a shield and provided with button holes, attaching means for the shield and cuff, and the button holes through the shield and cuff 60 being alined to receive a cuff button.

In testimony whereof I affix my signature.

GEORGE C. LEVY.
